Primary Examiner — Derrick E Holland

(57) **CLAIM**

The ornamental design for a trolley-case-shaped mobile energy storage device as shown and described.

DESCRIPTION

1. Trolley-case-shaped mobile energy storage device

1.1 : Perspective

1.2 : Perspective

1.3 : Front

1.4 : Back

1.5 : Left

1.6 : Right

1.7 : Top

1.8 : Bottom

The broken lines illustrate portions of the trolley-case-shaped mobile energy storage device that forms no part of the claimed design.
